US00D878186S

(12) **United States Design Patent** (10) **Patent No.:** **US D878,186 S**
(45) **Date of Patent:** **** Mar. 17, 2020**

(54) **SHEET FASTENING AND ANCHORING
COMPONENT**

(71) Applicant: **Nine IP Limited**, Auckland (NZ)

(72) Inventor: **Jonathan Dallas Toye**, Auckland (NZ)

(73) Assignee: **Nine IP Limited**, Auckland (NZ)

(**) Term: **15 Years**

(21) Appl. No.: **29/626,358**

(22) Filed: **Nov. 16, 2017**

(30) **Foreign Application Priority Data**

Jun. 1, 2017 (NZ) 423122

(51) **LOC (12) Cl.** **08-05**

(52) **U.S. Cl.**

USPC **D8/370**

(57) **CLAIM**

The ornamental design for a sheet fastening and anchoring component, as shown and described.

DESCRIPTION

FIG. 1 is a perspective view of a sheet fastening and anchoring component, showing my new design.

FIG. 2 is a front view thereof.

FIG. 3 is a rear view thereof.

FIG. 4 is a top view thereof.

FIG. 5 is a right side view thereof.

FIG. 6 is a left side view thereof; and,

FIG. 7 is a bottom view thereof.

The broken lines shown in the drawings depict a portion of the sheet fastening and anchoring component that form no part of the claimed design.

1 Claim, 7 Drawing Sheets
